UNITED STATES PATENT OFFICE

BERT E. DUTTON, OF BOULDER, COLORADO, ASSIGNOR TO THE DORR COMPANY, OF NEW YORK, N. Y., A CORPORATION OF DELAWARE

SEDIMENTATION APPARATUS

Application filed December 21, 1928. Serial No. 327,641.

This invention relates to improvements in sedimentation apparatus of the type which includes scraping or raking mechanism whose outer end is supported and driven along the periphery of the tank adapted to impel settled solids to a point of discharge, such as the apparatus shown in United States Letters Patent No. 1,356,608.

Apparatus of this type is designed to move only a certain maximum amount of settled solids having a predetermined resistance to the raking mechanism; and it sometimes occurs that due either to excessive feed, changes in the character of the solids, or changes in the proportion of solids in the feed, the settled solids on the bottom of the tank build up to a point where the resistance offered to the raking mechanism is above that for which the mechanism was designed, eventually resulting in warping or breaking the mechanism.

The general object of this invention therefore is to provide means for indicating an overload on the raking mechanism which will operate as soon as the overload becomes appreciable and before the danger point is reached, especially applicable to the type of apparatus shown in the patent mentioned above, which is often constructed in very large sizes, machines as large as 325 feet in diameter being in operation. With these large machines it is necessary to employ such large and heavy supporting and driving structures operating in the open under varying weather conditions, that ordinary means for indicating overload are unsuitable, cumbersome, unreliable or excessively expensive.

This object is attained by taking advantage of the fact that the speed of the outer end of the raking mechanism along the margin of the tank is reduced when the resistance to the rakes rises above normal; and a speed control device is employed connected to the outer end of the apparatus and traveling along the tank edge, with means for operating an indicator, alarm or other apparatus when the speed of such device falls below a predetermined minimum. The device operates generally on the basis of speed of rota-

tion caused by its travel along the tank edge, and is adapted to actuate an alarm or the like when its rotational speed falls below a predetermined point due to the slowing down of the settling tank mechanism. The preferred form shown is entirely electrical, eliminating the difficulty usually encountered with mechanical arrangements having moving parts, and comprises in general a central recess containing mercury or other conducting fluid, an insulated electrical contact in the recess, and a series of pockets or the like bordering on the recess which serve to carry some of the mercury away from the recess when the device rotates, thereby lowering the mercury level below the contact. The mercury drains back into the recess from the pockets, so that a balance is reached at a fixed speed of rotation with the mercury in the recess at a definite level, which of course is lowered when the rate of rotation increases and raised when the rate of rotation is reduced. This characteristic is utilized by setting the contact point at a suitable height where it will be out of contact with the mercury when the device rotates at normal speed; but upon reduction in speed and consequent rise in the mercury level the contact will be closed and the alarm operated.

Further objects are the provision of a small compact device unaffected by weather conditions and which can readily be attached to any type of traveling apparatus, regardless of the type of drive mechanism, being particularly adapted to be attached directly to the drive carriage of thickeners of the type set forth in the above patent and to travel along the supporting rail thereof.

Other objects and advantages will be apparent from the following description taken in connection with the accompanying drawings in which

Fig. 1 is a plan view of the outer or drive end of the raking truss of a thickener as described in the above mentioned patent, with the alarm device attached thereto;

Fig. 2 is a side elevation of said device;

Fig. 3 is a longitudinal vertical section through said device on line 3-3 of Fig. 2,

the contact element being shown in lower-most position for convenience; and

Fig. 4 is an end view from the right of Fig. 3 with the face plate removed, parts being broken away, the contact element being shown in operative position.

The settling tank 2 with wall 3, truss 25, rakes 29 and rail 31 all correspond to similar parts in the above mentioned United States Patent No. 1,356,608. Motor 33 mounted on the end of truss 25 drives wheel 36 resting on rail 31 through suitable gearing such as pulleys 40, belts 41 a worm on shaft 42, worm gear on shaft 43 and suitable bevel gear connections, not shown, with wheel 36. The precise type of drive mechanism is of course immaterial to this invention.

The alarm device is connected to the outer end of truss 25 so as to roll along the edge of tank 2, and preferably on rail 31. In the form illustrated the alarm device indicated generally at 44 is mounted on an arm 45 pivotally connected at 45a to the truss 25 to permit the alarm device to follow the rail 31.

The alarm device 44 comprises in general a body 46 in the general shape of a wheel preferably provided with flanges 47 to keep it on the rail 31. The wheel body 46 is mounted on a tubular stub shaft 48 carried in a bore in the offset end of arm 45 and adjustably clamped therein by set screw 49. A suitable bushing 50 butting against retaining shoulder 51 on stub shaft 48, with packing ring 52 of felt or the like, grease cup 53 and grease channel 54 may be included.

The outer face of body 46 is formed with an annular series of pockets 55 communicating through passages 56 with a central recess 57 adapted to contain mercury or other fluid conductor of electricity. A contact member 58 is located in recess 57 and is insulated from the body 46 and other parts of the alarm device 44 as by means of insulation blocks 59 and 60. In the form illustrated the block 59 is in the form of a disc set into the end of the stub shaft 48, and held in place by connecting bolt 61 whose head is inset in a recess 62 in the disc face and which bears at the other end against block 60 resting against a suitable shoulder 63 in shaft 48. The contact member 58 may be in the form of a fillister headed bolt passing radially through the insulation disc 59 and threaded into the head of bolt 61, the head of the member 58 being counter-sunk flush with the surface of disc 59.

Pockets 55 and recess 57 are suitably closed as by a removable cover plate 64 held in place against the face of body 46 by lag bolts 65 and having a central opening in register with the head of bolt 61 and closed by a threaded plug 70. Disc 59 is preferably proportioned to have only a slight clearance from the body 46 and cover plate 64 to form

a restricted pocket; and passages 56 may conveniently comprise shallow grooves in the face of body 46. Passages 66 connecting adjacent pockets 55 may likewise be formed by similar shallow grooves in the face of body 46, the cover plate 64 contacting with the face of the body 46 around pockets 55 to prevent passage of the conducting fluid to and from the pockets except through passages 56 and 66.

The contact member 58 is connected to one terminal of a suitable source of electricity B as by means of the insulated cable 67 connected to the end of bolt 61 and passing through conduit 68 set into the projecting end of the hollow stub 48. The mercury or other conducting fluid in central recess 57 is arranged for electrical connection with the other terminal, as by connecting said terminal to the rail 31 on which the wheel 48 rests, with a suitable device or signal such as the alarm bell 69 in circuit.

In operation mercury is introduced into the central recess 57 and fills the lower pockets 55 and said recess up to a predetermined level substantially below the center of the alarm device. The head of the contact member 58 is then adjusted to a suitable height, as by removing the plug 70 and rotating disc 59 and bolt 61. The head of contact member 58 is shifted in the direction in which the alarm device 44 will travel, but is positioned substantially below the level of the mercury in recess 57 when the device is at rest.

When the thickener is started up and truss 25 begins to travel along rail 31, the wheel body 46 is rotated as it rolls along the rail. This rotation lifts the pockets 55 containing mercury at the rear of the wheel and depresses those toward the front of the wheel, with the resultant lowering in the mercury level toward the front of the wheel to a point where the level is below the end of the contact member 58. The mercury will drain from the elevated pockets at the rear of the wheel through passages 56 into the rear portion of recess 57, and through passages 66 into adjacent pockets 55; while the pockets 55 which are brought below the mercury level at the front of the wheel 46 by its rotation are filled with mercury from recess 57 through passages 56, and likewise to a certain extent by lateral flow through passages 66 from adjacent pockets. Passages 56 and 66 are designed so as to restrict the rate of mercury discharge from the pockets 55 to the extent necessary to maintain a low mercury level at the forward side of recess 57 when the wheel 48 is rotating at normal speed, without carrying the mercury up over the top of the wheel at that rate of rotation.

With this arrangement the mercury level in recess 57 at the forward side of the wheel adjacent the contact member 58 will be maintained at an elevation determined by the

speed of rotation of the wheel 46, since more rapid rotation will cause the pockets 55 to carry more mercury upwardly on the ascending side of the wheel; while slower speed of rotation will afford more time for the mercury to flow back into the recess 57 thereby raising the level therein. Consequently the level of the mercury in recess 57 at the forward side will be in general proportional to the speed of rotation of the wheel 46 within the limits defined by the size of the passages 56 and 66 through which the mercury drains back into recess 57.

As the speed of rotation of the wheel 46 is directly proportional to the rate of travel of truss 25, the level of mercury in recess 57 will remain at a predetermined point when the truss is traveling at normal speed. If however, the truss for any reason should travel more slowly than normal, or should stop, the level of mercury in recess 57 will at once rise; and the device is very sensitive to slight changes in rate of rotation. The head of contact member 58 is therefore set slightly above the mercury level in recess 57 when the truss 25 is traveling at normal speed, but below the mercury level in said recess when the truss is running at a lower speed. When the mercury level rises to a point where a contact is made with the member 58 the electrical circuit is closed and the alarm 69 or other electrical device is actuated, giving timely warning of the difficulty which has caused the truss 25 to slow down. By suitable adjustment of contact member 58 the precise slower speed at which the electrical circuit will be established can be regulated with great accuracy.

It will be apparent that a number of other arrangements, electrical and otherwise, may be employed for the same purpose within the scope of this invention. However, the arrangement disclosed is compact, simple, completely protected against weather conditions, and by using mercury is free from pitting and other difficulties encountered normally when opening and closing electrical circuits, especially when relatively slow contacts are made or broken. The device is likewise adapted for use on machines in which the outer end of the truss 25 or its equivalent follows a non-circular path.

While an alarm device is shown as being adapted to travel on the traction surface of the sedimentation tank, it is to be distinctly understood that departures from such an arrangement are contemplated. For example, the device may have engagement with a separate traction surface either within or without the wall of the sedimentation tank.

60 I claim:

1. A tractionally driven sedimentation apparatus comprising a scraping device adapted to travel over the bottom of a sedimentation tank to impel settled solids to a discharge, and means operable by engagement

with the traction surface of the sedimentation apparatus, and responsive to variations in the rate of travel of said device, for producing a predetermined action corresponding to a selected variation in the rate of travel.

2. The combination with a tractionally driven sedimentation apparatus comprising a scraping device adapted to travel over the bottom of a sedimentation tank to impel settled solids to a discharge, of means operable by engagement with a traction surface and responsive to variations in the rate of travel of said device for producing a predetermined action corresponding to a selected variation in the rate of travel.

3. The combination with a tractionally driven sedimentation apparatus comprising a scraping device adapted to travel over the bottom of a sedimentation tank to impel settled solids to a discharge, of electrical means cooperating with a traction surface and responsive to variations in the rate of travel of said device for producing a predetermined electrical action corresponding to a selected variation in the rate of travel.

4. The combination with the wall of a sedimentation tank of a sedimentation apparatus comprising a scraping device adapted to travel over the bottom of a sedimentation tank to impel settled solids to a discharge, of means traveling with said device and engaging the said wall to be actuated thereby for producing a predetermined action corresponding to a selected variation in the rate of travel.

5. The combination with the tank of a sedimentation apparatus comprising a scraping device adapted to travel over the bottom of the sedimentation tank to impel settled solids to a discharge, of means traveling with the device and maintained in rolling engagement with the tank to be actuated by said engagement for producing a predetermined action corresponding to a selected variation in the rate of travel.

6. The combination with a margin of a sedimentation tank of a sedimentation apparatus, comprising a traveling scraping device for impelling settled solids to a discharge and having an end supported on and adapted to travel along said margin, of means operatively associated with said end and maintained in rolling contact with the margin of the tank for producing a predetermined action responsive to a selected variation in the rate of travel.

7. The combination with the margin of a sedimentation tank of a sedimentation apparatus comprising a traveling scraping device for impelling settled solids to a discharge and having an end supported on and traveling along said margin, of electrically actuated means operable in an electrical circuit for propelling said end along the margin of the tank, and electrical means operable in

- a separate circuit and operatively associated with said end and traveling therewith for producing a predetermined action responsive to variations in the rate of travel of said device.
8. The combination with a sedimentation tank of a sedimentation apparatus comprising a scraping device adapted to travel over the bottom of the tank to impel settled solids to a discharge, of a wheel mounted on and traveling with said device and maintained in rolling contact with the tank, and means responsive to variations in the rate of rotation of the wheel for producing a predetermined action responsive to a selected variation in the rate of travel.
9. The combination with the wall of a sedimentation tank of a sedimentation apparatus comprising a traveling scraping device for impelling solids to a discharge, of means cooperating with the wall for closing an electrical circuit when the rate of travel of the scraping device is less than the predetermined minimum rate, said means including a casing adapted to travel on the tank, a reservoir in the casing, an electric conducting liquid in the reservoir, and insulated terminal positioned for contact with the liquid when the liquid reaches a predetermined level, electrically actuated means for producing a predetermined action and an electrical circuit for connecting the liquid and said terminal with said means to actuate the latter when the liquid and the terminal make contact to close the circuit.
10. The combination with the wall of a sedimentation tank of a sedimentation apparatus comprising a traveling scraping device for impelling solids to a discharge, of means cooperating with the wall for closing an electrical circuit when the rate of travel is less than the predetermined minimum rate, said means including a casing adapted to travel on the wall, a reservoir in the casing, an electric conducting liquid in the casing, a terminal positioned for contact with the liquid when the liquid reaches a predetermined level, and means for varying the level of the liquid in said reservoir in accordance with variations in the rate of rotation of the casing.
11. The combination with a traction surface of a sedimentation apparatus comprising a traveling scraping device for impelling settled solids to a discharge, of means on the traction surface for closing an electrical circuit when the rate of travel is less than a predetermined minimum rate, said means including a casing adapted to travel on the traction surface, a reservoir in the casing, an electric conducting liquid in the reservoir, an insulated terminal positioned for contact with the liquid when the liquid reaches a predetermined level, and means for withdrawing portions of said liquid from the reservoir during rotation of the casing and returning said liquid to the reservoir at a rate determined by the rate of rotation.
12. The combination with a traction surface of a tractionally driven sedimentation apparatus comprising a scraping device for impelling settled solids to a discharge, of means on the traction surface for closing an electrical circuit when the rate of travel is less than a predetermined minimum rate, said means including a casing adapted to travel on the traction surface, a reservoir in the casing for an electric conducting liquid, an insulated terminal positioned for contact with the liquid when the liquid reaches a predetermined level, said casing including an annular series of recesses communicating with the reservoir adapted to withdraw liquid from the reservoir to reduce the liquid level therein during rotation and provided with draining outlets for returning the liquid to the reservoir.
13. The combination with a traction surface of a tractionally driven sedimentation apparatus comprising a traveling scraping device, of a casing operatively associated with the traction surface and adapted to roll on the same at a rate corresponding to the rate of travel of the device, said casing including a reservoir for electric conducting liquid, and an annular series of recesses extending around the reservoir and communicating therewith through restricted openings adapted to withdraw liquid from the reservoir during rotation of the casing together with the series of recesses around the reservoir and to return the withdrawn liquid to the reservoir through said openings, the construction and arrangement being such that the level of liquid in the reservoir will have a predetermined relationship to the speed of rotation in the casing; and an insulated contact member extending into the reservoir and adapted to make electrical contact with said liquid when the liquid reaches a predetermined point.
14. The combination with a traction surface of a tractionally driven sedimentation apparatus comprising a traveling scraping device, of a casing operatively associated with the traction surface and adapted to roll therealong at a rate corresponding to the rate of travel of the device, said casing including a reservoir for electrically conducting liquid, an annular series of recesses extending around the reservoir and communicating therewith through restricted openings, and adapted to withdraw liquid from the reservoir during rotation of the casing together with the series of recesses around the reservoir and to return the withdrawn liquid to the reservoir through said openings, the construction and arrangement being such that the level of liquid in the reservoir will have a predetermined relationship to the speed

of rotation of the casing; and an insulated contact member extending into the reservoir and adapted to make electrical contact with said liquid when the liquid level reaches a 5 predetermined point, and means for adjusting the position of the contact member to regulate the liquid level at which contact is made.

In testimony whereof I affix my signature.
